United States Patent

Des. 235,163
Patented May 20, 1975

235,163

SPECTACLE FRONT

Anthony Shindler, Brookline, Mass., assignor to American Optical Corporation, Southbridge, Mass.

Filed Nov. 30, 1973, Ser. No. 420,752

Term of patent 14 years

Int. Cl. D16—06

U.S. Cl. D57—1 F

FIG. 1

FIG. 2

FIG. 3

FIG. 4

FIG. 5

FIG. 1 is a front perspective view of a spectacle front embodying my new design;

FIG. 2 is a front elevational view thereof;

FIG. 3 is a top plan view thereof;

FIG. 4 is an elevational view of one side of the spectacle front, the opposite side thereof being of substantially the same appearance; and

FIG. 5 is an enlarged rear perspective view of a portion of the bridge of the spectacle front.

The frame front is shaded to indicate contrast.

I claim:

The ornamental design for a spectacle front, as shown and described.
